UNITED STATES PATENT OFFICE.

JOHN E. GILSON, OF PORT WASHINGTON, WISCONSIN, ASSIGNOR TO GILSON MANUFACTURING COMPANY, OF PORT WASHINGTON, WISCONSIN.

PORTABLE FRAME FOR TRANSMISSION-GEARING.

1,096,104.

Specification of Letters Patent.

Patented May 12, 1914.

Application filed February 16, 1911. Serial No. 608,945.

To all whom it may concern:

Be it known that I, JOHN E. GILSON, a citizen of the United States, and resident of Port Washington, in the county of Ozaukee and State of Wisconsin, have invented certain new and useful Improvements in Portable Frames for Transmission-Gearing; and I do hereby declare that the following is a full, clear, and exact description thereof.

10 The primary object of my invention is to provide simple, economical and effective transmission gearing and frame therefor, the construction and arrangement being such that interchangeable counter-shafts are 15 provided and arranged to be adjustably mounted upon longitudinal struts, which struts are secured at their opposite ends to the engine body comprising one of the frame members, the struts being preferably in the 20 form of U-shaped loops. The counter-shafts are provided with transmission gear whereby power is applied to machine elements in juxtaposition to the frame.

With the above objects in view my invention consists in various structural features and combination of mechanical elements as hereinafter described with reference to the accompanying illustrations and subsequently claimed.

30 In the drawings Figure 1 represents a plan view of an internal combustion engine provided with a gear transmission attachment embodying the features of my invention; Fig. 2, a side elevation of the same with parts broken away and parts in section to more clearly illustrate certain structural features, and Fig. 3, a detail plan view illustrating a counter-shaft equipped with a transmission gear in the form of a series of 35 pulleys, which counter-shaft may be substituted for the counter-shaft and its transmission gear as illustrated in Fig. 1 of the drawings.

Referring by characters to the drawings 1 45 represents an engine base provided with feet 2, to which engine base is secured the cylinder 3, the walls of which extend upwardly to form an open water cooling tank 4 as shown, the entire structure constituting a 50 master casting that forms the basic part of a portable frame for transmission gearing.

Mounted upon the base 1 is the usual crank-shaft 5 that is connected to the piston

6 by a pitman 7, the crank-shaft being also provided with standard fly-wheels 8, and a 55 drive-wheel 9, which, in this instance, is shown in the form of a pulley. The engine is also provided with the usual valve mechanism 10 that is operated by a cam-carrying gear-wheel 11 through a pinion 12 carried 60 by the crank-shaft, all of which construction forms no part of my present invention.

The cylinder 3 is provided with apertured ears 13 that extend laterally in either direction from the side-walls thereof. The ends 65 of upper stretches 14 of longitudinal struts are secured to these ears 13, which struts comprise open end loops having vertically disposed stretches 15 and bottom stretches 16 that extend under the feet of the engine 70 base and are secured thereto by bolts 17, the vertical stretches of the struts being disposed rearwardly of the engine cylinder or in the opposite direction to which power is applied to the crank-shaft. The struts are 75 each preferably bent up from a single piece of U-shaped angle-iron, their bottom stretches being supported upon front and rear truck-members 18, 18', it being understood, however, in some instances, said truck 80 members may be supplemented by suitable skids.

The vertical stretch 15 of each strut is provided with a series of apertures 19 for the reception of retaining bolts 20 of a supporting member 21 of a two part box, the cap member 22 of the box being hinged to the supporting member 21, which latter has a slotted flange 23 for engagement with one set of the retaining bolts 20, whereby said 90 cap member is secured. A counter-shaft 24 is journaled in the boxes, which counter-shaft carries a pulley 9^a that is in belt gear connection with the crank-shaft pulley 9. A hanger 25 is provided with boxes at one 95 end thereof, whereby said hanger is suspended about the counter-shaft 24. The opposite end of the hanger carries a single box 27, into which is journaled an arbor 28 having a gear-wheel 29 secured to one end and 100 a disk 30 at the opposite end thereof. The arbor is also journaled in bearings 31 of a bifurcated clip 32, which clip bearings abut the opposite ends of the hanger-box 27, whereby a hinge connection is formed about 105 said arbor relative to the clip and hanger.

The clip has an apertured flange for the reception of retaining bolts 33, that engage a separable saddle member 34 of said clip, whereby the same may be readily attached 5 to a pump column 35, as shown in Figs. 1 and 2, or other machine element. Both the gear-wheel 29 and disk 30 carry crank-pins 29^a and 30^a respectively to which crank-pins are connected pitmen 36, 36^a, the pitmen 10 being provided for connection with the pump piston rod 37 by any suitable means, not shown.

The counter-shaft carries a toothed pinion 38, by means of which drive therefrom 15 is imparted to the gear-wheel 29, through an idle pinion 39 that is interposed between the first named pinion and gear-wheel, the idle pinion 39 being journaled upon a stud 40 that is carried by the hanger 25. The clip, 20 gear-wheel 29, and disk 30, with their various connections carried by the bracket, thus constitute a pump-jack, which as stated, constitutes means whereby the engine can be readily coupled to the pump or other mechanical element to which power is to be applied. The hanger being in hinge connection 25 with the counter-shaft and arbor, permits ample scope for adjustment with relation to elevation of the gear connection 30 between said engine and pump. It will also be observed that the journal boxes of the counter-shaft may be adjusted to various elevations and secured by the retaining bolts 20 that are fitted into any one of the separate 35 sets of the strut apertures. When it is desired to supplement the counter-shaft driving-gear illustrated in Figs. 1 and 2 of the drawings with a counter-shaft equipped with a stepped pulley 41, as shown in Fig. 40 3, the same may be readily accomplished by loosening one set of the retaining bolts 20 whereby the hinged cap sections 22 of the boxes may be swung backward for the removal of counter-shaft 24, the counter-shaft 45 24^a carrying the pulleys 41 being then dropped into position within the boxes.

It is desirable to provide means for tightening the belt through which motion is imparted to the counter-shaft pulley 9^a from 50 the crank-shaft pulley 9 and with this in view one end of an inverted L-shaped brace beam 15' is secured to a strip 16 of one of the struts. The brace beam 15' is also secured to the upper stretch 14 of this strut, a 55 leg 15'' being extended across the frame and is secured at its end to the upper stretch 14 of the opposite strut thus forming a brace for the gear-carrying frame comprising the parallel struts previously described. The 60 vertical stretch of the brace beam 15' is slotted for the reception of a stud 9^b that is adjustably secured thereto by means of a retaining nut in threaded engagement with said stud and mounted upon the stud is a 65 belt tightening roller 9^c adapted to operate

upon one stretch of the driving belt between pulleys 9 and 9^a whereby said belt is adjusted as to slack. The counter-shaft 24^a, as shown, is also equipped with a clutch-pulley 42, whereby power may be applied 70 to a separator or any machine or element wherein it is preferable to employ a clutch-pulley transmission.

The idle pinion 39, through which power is transmitted from the counter-shaft to the gear-wheel 29 is inserted for the purpose of overcoming the reverse drive of said gear-wheel which would occur, should the same be directly meshed with the counter-shaft pinion 38, but it should be understood that, in some instances, reverse drive upon said gear-wheel may be desirable, in which case the idle pinion 39 would be dispensed with. It is also obvious that any suitable form of gearing may be employed to transmit power from the engine crank-shaft to the counter-shaft and from thence to the machine element other than that shown and described.

The front truck 18 is provided with a fifth-wheel while the rear member 18' is rigidly secured to the struts. The front truck member comprises a tubular axle 43 which is fitted with a centrally disposed saddle 44, the same being secured thereto by a U-shaped clip-bolt 45 having threaded ends 95 that engage ears of the saddle 44, the bolt being clamped thereto by suitable nuts in threaded engagement therewith.

The saddle 44 is provided with a circular face-plate having a centrally disposed shoulered aperture for the reception of a headed king-bolt 47, which king-bolt passes through an apertured fifth-wheel disk 48, the disk being provided with a rectangular hollow block extension 49 that is seated within a 100 transversely disposed U-shaped girder 50. This girder is secured to the bottom stretches 105 16 of the struts by the bolts 17, which, as previously mentioned, also anchor the engine-base to said struts.

The rear truck-member comprises a hollow axle 43^a, which axle is secured to the bottom struts 16 by bolts 56 that pass through apertures in the axle and alined apertures in said struts, there being hollow spacing 110 chairs 57 interposed between the struts and axles. Each chair is provided with longitudinal flanges that engage the side faces of the struts whereby a rigid joint is formed therebetween, the lower walls of the chairs 115 being also provided with curved seats into which the axle is seated. The rear axle is provided with truck-wheels 54^a that are held against lateral play.

While I have shown and described a specific form of truck upon which the engine is mounted for transportation, it is understood that I do not wish to claim the same or be confined to the structure of said truck, it being within the scope of my invention.

tion to mount the engine upon skids in some instances as a substitute for the truck-wheels.

I claim:

1. A portable frame for transmission gearing comprising a pair of looped struts, boxes secured to vertical stretches of the struts adapted to receive a counter-shaft, and a master casting mounted on the lower horizontal stretches of said struts and provided with lateral ears connected to upper horizontal stretches of the aforesaid struts.

2. A frame for portable transmission gearing comprising a pair of struts having upper and lower longitudinal stretches connected by vertical stretches, a master casting having its base secured to the lower stretches of the struts, whereby the same are cross-connected, ears extending from the master casting, means for securing the ears to the upper stretches of the struts, whereby the same are cross-connected, and boxes carried by the vertical stretches of the struts adapted to receive a counter-shaft.

3. A portable transmission mechanism comprising an engine body having a base, a cylinder supported thereon, and a crank-shaft mounted upon said base; ears extending from the cylinder, looped struts having their respective ends secured to the ears and engine body base, and a gear-carrying counter-shaft mounted upon the struts in belt drive connection with the engine crank-shaft.

4. A portable transmission mechanism comprising an engine body having a base, a cylinder supported thereon, and a crank-shaft mounted upon said base; ears extending from the cylinder, looped struts having their respective ends secured to the ears and engine body base, boxes adjustably mounted upon vertical stretches of the looped struts, and a gear-carrying counter-shaft journaled in the boxes in belt-drive connection with the engine crank-shaft.

45 5. A portable transmission mechanism comprising an engine body base, feet extending from the base, and a cylinder and crank-shaft mounted upon said base, ears extending from the cylinder, longitudinal looped struts having their respective ends secured to the cylinder ears and base feet, the struts being provided with vertical apertured stretches, boxes fitted to the vertical stretches, securing bolts for the boxes engageable with the apertures in said vertical stretches of the struts, and a gear-carrying counter-shaft journaled in the boxes, the counter-shaft being in belt driven connection with the engine crank-shaft.

60 6. A portable transmission mechanism comprising an engine body having a base, a cylinder supported thereon, and a crank-shaft mounted upon the base forward of the cylinder, longitudinally disposed looped struts having their ends secured to the cylin-

der and base, the struts being extended rearward of said cylinder and provided with vertical stretches, boxes adjustably mounted upon the vertical stretches of said struts, and a gear-carrying counter-shaft journaled 70 in the boxes in belt-drive connection with the engine crank-shaft.

7. A portable transmission mechanism comprising an engine body; the crank-shaft thereof, longitudinal struts secured to the 75 engine body, a gear-carrying counter-shaft mounted upon the struts in drive connection with the engine crank-shaft, a hanger journaled about the counter-shaft and an arbor journaled in the opposite end of the hanger 80 in gear connection with the aforesaid counter-shaft.

8. A portable transmission mechanism comprising an engine body; the crank-shaft thereof, longitudinal struts secured to the 85 engine body, a gear-carrying counter-shaft mounted upon the struts in drive connection with the engine crank-shaft, a hanger journaled about the counter-shaft, an arbor journaled in the opposite end of the hanger in 90 gear connection with the aforesaid counter-shaft, and an attaching clip journaled about the arbor.

9. A portable transmission mechanism comprising an engine body; the crank-shaft, 95 longitudinal struts secured to the engine body, a counter-shaft journaled upon the struts in belt-gear connection with the engine crank-shaft, a hanger having one end journaled about the counter-shaft, an arbor 100 journaled in the opposite end of the hanger, an attaching clip axially mounted about the arbor, a crank-disk secured to one end of said arbor, a cranked gear-wheel secured to the opposite end of the aforesaid arbor, a pinion carried by the counter-shaft, a stud extending from the hanger, and an idle pinion mounted upon the stud in meshed engagement with the counter-shaft pinion and cranked gear-wheel of said arbor. 110

10. A portable transmission mechanism comprising an engine body; a crank-shaft journaled thereon, longitudinal struts secured to the body, split box members secured to the struts having hinged cap sections, 115 means for securing said hinged cap sections, a detachable counter-shaft journaled in said boxes, an arbor in gear with the counter-shaft, a belt-drive connection between the arbor and engine crank-shaft, and power 120 transmission gear carried by the arbor.

11. A portable transmission mechanism comprising an engine body having a base, a cylinder supported thereon, a crank-shaft journaled upon the base, laterally disposed ears extending from opposite sides of the cylinder, a pair of looped struts having their upper stretches secured to the cylinder ears and their lower stretches secured to the base, the struts being provided with aper- 125

- tered vertical stretches, boxes having retaining bolts that are adapted to engage the strut apertures, a counter-shaft journaled in the boxes, pulleys mounted upon the engine crank-shaft and counter-shaft and in belt connection with each other, a hanger having bearings at one end loosely mounted about the counter-shaft, a bearing at the opposite end of the hanger, an arbor journaled in the bearing, a clip having bearings loosely mounted about the arbor, the clip being provided with means for securing the same to a fixed member, a disk mounted upon one end of the arbor, a gear-wheel mounted upon the opposite end of the arbor and in gear connection with the counter-shaft, cranked pins extending from the disk and arbor gear-wheel, and pitmen connecting the cranks.
12. A portable transmission mechanism comprising an engine body having a base, a cylinder supported thereon, and a crank-shaft mounted upon said base; ears extending from the cylinder, looped struts having their respective ends secured to the ears and base, a gear-carrying counter-shaft mounted upon the struts, a pulley carried by the crank-shaft, a second pulley carried by the counter-shaft in belt drive connection with the crank-shaft pulley, a brace beam secured to the upper and lower stretches of one of

the struts, and an adjustable belt-tightening roller carried by the brace beam for engagement with the belt aforesaid.

13. A portable transmission mechanism comprising an engine body having a base, a cylinder supported thereon, and a crank-shaft mounted upon said base; ears extending from the cylinder, looped struts having their respective ends secured to the ears and base, a pulley carried by the crank-shaft, a second pulley carried by the counter-shaft in belt-drive connection with the crank-shaft pulley, an inverted L-shaped base beam having a vertical stretch secured to the upper and lower stretches of the struts, the horizontal arm of the inverted L-shaped beam being extended from one strut of the frame to the opposite strut, securing means for said arm and upper stretch of the opposite strut, and a belt-tightening roller carried by the vertical stretch of the brace beam for engagement with the belt aforesaid.

In testimony that I claim the foregoing I have hereunto set my hand at Port Washington in the county of Ozaukee and State of Wisconsin in the presence of two witnesses.

JOHN E. GILSON.
